1 Claim. (Cl. 313—63)

This invention relates to accelerating tubes suitable for use with electrostatic generators, e.g. of the Van de Graaff type.

The performance of an electrostatic generator as a particle accelerator is normally limited by the quality of the accelerating tube, at high vacuum, through which the particles (positive or negative ions) are accelerated. The limitation manifests itself through the X-rays generated by the electrons which stream back to the (positive) high tension electrode through the evacuated region. The X-rays, which can be readily detected outside the pressure vessel enclosing the generator, cause high ionisation currents in the high pressure gas in the vessel, which constitutes the insulator against high voltage breakdown. As both the electron currents and the concomitant X-rays rise steeply above a given voltage threshold, machine performance is commonly limited by the ionization currents liberated by the X-rays in the gas of the pressure vessel.

The origin of these electron currents is obscure. The tube is commonly designed with say 150 electrodes separated by glass rings 1" thick. The electrodes are commonly plates or dishes in which the planar region adjacent to the beam (which passes through a hole in the plate or dish) is normal to the direction of the beam. Two electrodes separated by a glass ring in vacuum will withstand up to 200 kv., so that, if the strength of the system were linear, the composite tube should withstand a voltage of 30 mv. In practice, however, such a tube would be unlikely to withstand more than 5 mv. without heavy "electron loading" setting in. It is clear that some multiplication mechanism (or mechanisms) is at work, but the phenomenon has not been elucidated.

According to the present invention an accelerating tube comprises a plurality of electrodes whereof the planar region adjacent the beam is normal to the tube axis followed by a plurality of electrodes whereof the planar region adjacent the beam is tilted relative to a plane normal to the tube axis, the azimuthal direction of tilt of successive electrodes being incrementally varied to form at least one pair of consecutive 360° spirals spiralling in opposite directions, and the increments being such that the net displacement and angular deviation of the beam in traversing the pair of spirals are substantially zero.

To enable the nature of the present invention to be more readily understood, attention is directed, by way of example, to the accompanying drawings wherein:

FIG. 1 is a sectional elevation of a tilted electrode.
FIG. 2 is a plan view of the electrode of FIG. 1.

FIG. 3 is a simplified sectional elevation of an accelerating tube embodying the invention.

FIG. 4 is a sectional elevation of a modified tilted electrode.

As already stated, it is common practice in accelerating tubes to use electrodes in the form of plates or dishes in which the planar area adjacent to the beam is normal to the beam. The present invention involves the use of electrodes in which this planar area makes an angle with the plane normal to the tube axis, and a dished electrode of this kind is shown in FIGS. 1 and 2. It will be seen

that the planar area 1 adjacent the hole 2, through which the beam passes, makes an angle θ with the normal to the axis of the beam, which is indicated by the arrow 4. The two additional holes 3 are provided to make the tube easier to pump out. The direction of tilt of this electrode is indicated by the arrow 5 in FIG. 2.

If a succession of the electrodes shown in FIG. 1 is used, the beam will experience a sideways deflection which is not subject to later correction. This sideways deflection is a maximum at low beam velocities; if the beam is travelling at high velocity, the time that it spends in the vicinity of two electrodes is small, and the deflection experienced is correspondingly low. The same is true of whatever particles are responsible for the multiplication mechanism of the phenomenon of electron loading; if the electrodes where they originate are tilted with respect to the beam, as in FIG. 1, they will experience a sideways deflection which will persist throughout subsequent acceleration and will cause them to strike electrodes further along the tube with energies far less than they would attain by acceleration throughout the length of the machine. Since the X-ray yield and penetration increase rapidly with increasing electron energy, the loading produced by such X-rays will be very greatly reduced, if not altogether suppressed.

Equally, however, a succession of electrodes tilted at a constant angle throughout an accelerating tube would rapidly deflect the desired particle beam until it hit the electrodes. Now, as already indicated, the effect of loading is by no means linear, being small for short lengths of tube, and the effect of the deflection produced by tilted electrodes is small for particles which have attained a high velocity. The present accelerating tube takes advantage of these effects in the manner shown in FIG. 3, in which the successive electrodes are numbered E1, E2, etc., from the input end of the tube. At the input (high voltage) end, where the particle velocity is low, a section of ordinary tube is used consisting of 29 electrodes normal to the axis of the tube. In this section the particles are accelerated to about 1.5 mv. From electrode 30 onwards, however, the tilted electrodes shown in FIGS. 1 and 2 are used, the angle θ being 10°. If all the tilted electrodes were parallel, the resultant deviation of the beam from the tube axis would not be negligible. To avoid this deviation the azimuthal direction of the tilt of successive electrodes is incrementally varied, i.e. the electrodes are spiralled, so that the direction of deflection is also a spiral. If the azimuthal direction of tilt of electrode 30 is taken as $\alpha=0^\circ$ (the datum), then with a suitable rate of change of α between successive electrodes the net deflection of the beam can be made negligible at electrode 45 where $\alpha=360^\circ$. The arrow 6 in FIG. 2 indicates the position of the arrow 5 for an electrode whose azimuthal direction of tilt is α° relative to the datum.

There must be taken into account, however, not only the deflection, i.e., the angular deviation of the particle beam from the original axis, but its displacement from that axis. It can be shown that for the 63-electrode tube of FIG. 3 this displacement is quite large at electrode 45 (about 0.1 inch, in the azimuthal direction of $\alpha=90^\circ$). The displacement can be corrected by using a second spiral spiralling in the opposite direction. Thus in FIG. 3 the first spiral ends at electrode 45 where $\alpha=-360^\circ$; the second spiral begins at electrode 45 and ends at electrode 63 where $\alpha=-360^\circ$. By suitably varying the rate of change of α between successive electrodes as hereinafter described, the net displacement as well as the net deviation can be made negligibly small.

Since the velocity of the particles increases as they traverse each spiral, it follows that the angular increments between successive electrodes require to be greater at

the beginning than at the end of each spiral. Let it be assumed that the electrodes are equi-spaced along the tube (so that the number of each electrode is a measure of its distance from the input end), that the first spiral starts at electrode n_0 and ends at electrode n_1 , and that the second (reverse) spiral starts at electrode n_1 and ends at electrode n_2 . Then, for the net deviation in the first spiral to be negligible it can be shown that

$$\alpha_n = \frac{2\pi(\sqrt{n} - \sqrt{n_0})}{\sqrt{n_1} - \sqrt{n_0}}$$

where $\alpha_{n_0} = 0^\circ$, and for the net deviation in the second (reverse) spiral to be negligible that

$$\alpha_n = \frac{2\pi(\sqrt{n} - \sqrt{n_1})}{\sqrt{n_2} - \sqrt{n_1}}$$

where $\alpha_{n_1} = 0^\circ$. Similarly, for negligible displacement of the beam it can be shown that

$$\sqrt{n_2} - \sqrt{n_1} = \sqrt{n_1} - \sqrt{n_0}$$

The following table gives values of α for the 63-electrode tube shown in FIG. 3, which meet the above conditions. In this design $\theta = 10^\circ$ and the hole 2 is $1\frac{1}{2}$ inches in diameter.

Electrode No.	α°	Electrode No.	α°	Electrode No.	α°
1-29	40	40	+250	52	-154
30	0	41	+272	53	-174
31	+28	42	+294	54	-194
32	+54	43	+316	55	-214
33	+80	44	+338	56	-233
34	+106	45	+360 = 0	57	-252
35	+131	46	-23	58	-270
36	+155	47	-45	59	-288
37	+179	48	-67	60	-306
38	+203	49	-89	61	-324
39	+227	50	-111	62	-341
		51	-133	63	-360

The 63-electrode tube described with reference to FIG. 3 is specifically designed for a total tube voltage of about 2.5 mv. (i.e. 40 kv. per electrode), the electrodes being spaced 1 inch apart. In the general case various parameters have to be optimised, the factors affecting these parameters being:

(a) The acceleration which electrons emitted from the electrodes may receive before striking an electrode further up the tube.

(b) The distance by which the particle beam may be displaced from the beam axis after the first spiral. Clearly this displacement must be such that, after taking account of structural tolerances, the cross-sectional diameter of the beam etc., interception of the beam by the electrodes is highly improbable.

Taking these factors into account, two parameters which are to a certain extent arbitrary are:

(i) The angle of tilt, θ , of the individual electrodes. It can be shown that in the described design with a hole diameter of $1\frac{1}{2}$ inches and $\theta = 10^\circ$, the probably maximum electron energy is about 500 kv. With a smaller value of θ the maximum electron energy would be greater, and with a greater angle the beam displacement after

the first spiral would be greater. The value chosen, 10° , represents a reasonable compromise.

(ii) The mean rate of variation of the angle α . If this rate were too slow, part of the beam might be intercepted by the electrodes, e.g. in the example of FIG. 3 if one complete spiral (360°) occupied all 60 electrodes, it can be shown that the displacement of the particle beam would amount to about 0.4 inch. This estimate is naturally affected by the overall length of the tube and the applied voltage; as the velocity of the beam particles becomes greater the beam deviation diminishes and hence also the total displacement. For a long tube, therefore, the optimum compromise is to choose a rate of spiralling which is high where the particle velocity is low and vice versa. Thus for a long tube several pairs of spirals having different mean spiralling rates may be necessary.

In cases where the electrode size does not permit the machining of the pumping holes 3 (FIG. 1), adequate pumping speed can be combined with electron suppression by increasing the diameter of the hole 2 and offsetting it from the beam axis 4 towards the lower side of the electrode. FIG. 4 shows such an electrode in which the hole 2' is increased to 3 inches diameter and is offset so that the distance from the beam to the nearest point 7 on the circumference of the hole is $\frac{3}{4}$ inch. Electrons leaving this electrode at the point 7 will traverse the tube across the axis and strike an electrode at the point further up the tube where the direction of tilt is reversed, i.e. $\alpha = 180^\circ$. The overall effect is then equivalent to tube of electrodes having coaxial $1\frac{1}{2}$ inch diameter holes. To limited extent this effect depends on the rate of spiralling and is linked with the factor (b) already considered. For example, if the spiral is too fast, the electrons may miss the electrode edge after the first half-spiral, and travel appreciably further, thereby generating X-rays of higher energy. However in practical cases the rate of spiralling coincides with the rate required if the electrons are to strike the electrodes at the end of the first half-spiral.

We claim:

An accelerating tube for an electrostatic generator comprising a plurality of electrodes whereof the planar region adjacent the beam is normal to the tube axis followed by a plurality of electrodes whereof the planar region adjacent the beam is tilted relative to a plane normal to the tube axis, the azimuthal direction of tilt of successive electrodes being incrementally varied to form at least one pair of consecutive 360° spirals spiralling in opposite directions, and the increments being such that the net displacement and angular deviation of the beam in traversing the pair of spirals are substantially zero.
